UNITED STATES PATENT OFFICE.

WALTER D'A. RYAN, OF WATERTOWN, SOUTH DAKOTA, ASSIGNOR TO GENERAL ELECTRIC COMPANY, A CORPORATION OF NEW YORK.

DIFFUSING-CLUSTER.

1,022,878.

Specification of Letters Patent.

Patented Apr. 9, 1912.

Application filed August 30, 1909. Serial No. 515,139.

To all whom it may concern:

Be it known that I, WALTER D'A. RYAN, a subject of the King of Great Britain, residing at Watertown, county of Codington, 5 State of South Dakota, have invented certain new and useful Improvements in Diffusing-Clusters, of which the following is a specification.

This invention relates to incandescent 10 electric lighting and especially to devices for supporting one or a group of incandescent electric lamps in such a manner as to produce an economical distribution of the light.

One object of the invention is to facilitate 15 the use of incandescent lamps having clear bulbs and of high intrinsic brilliancy, without producing an unpleasant glare or dazzling the eyes of the observer.

Another object is to enable lamps of different sizes to be employed in the same cluster, means being provided for raising and lowering their support so that they can be properly positioned with reference to the in- 20 closing globe or diffuser.

Before taking up in detail the construction of this cluster, attention should be called to the fact that in order to diffuse the rays emitted by an incandescent electric lamp it is customary to provide it with a 25 translucent bulb or globe, which may be either frosted inside or outside, or made of opalescent glass. It is well known that when such a translucent medium is placed in the path of light rays a large percentage of 30 them is prevented from passing through and is converted into heat. In an incandescent electric lamp this heat is not only useless, but is positively injurious, because it facilitates the consumption of the incandescent 35 filament and thereby reduces the life of the lamp by thirty or forty per cent. Inasmuch as the intensity of illumination varies inversely as the square of the distance from the source, it follows that the higher the intrinsic brilliancy of the source the greater 40 must be the distance therefrom of the diffusing envelop, in order that said envelop may reduce the intrinsic brilliancy to a degree which is safe for the eye of the ob- 45 server. It is therefore better practice to use a clear bulb, which gives the lamp a longer life, and to surround it with a diffusing outer envelop big enough to keep the intrinsic brilliancy down to normal.

50 My invention is therefore of especial value

in connection with the modern lamps of high intrinsic brilliancy, especially those having tungsten filaments. In carrying it into effect, I provide a reflector, a platform supported above it and vertically adjustable, 55 one or more lamps suspended from said platform through openings in said reflector, a diffusing globe surrounding the clear bulbs of said lamps, a sheet metal casing above the reflector, and suitable means for suspending this structure and conveying current thereto. Ventilating openings and passages are arranged to permit a flow of air up through the globe and past the lamps and out 60 through vents in the casing.

In the accompanying drawing, Figure 1 is a sectional elevation of a cluster embodying my invention, and Fig. 2 shows a fragment of the reflector with one of the openings through which the necks of the lamps 65 pass up into their receptacles.

At the center of the cluster is an upright stem 1, preferably tabular and attached at its lower end to the center of a substantially horizontal nickel-plated sheet metal reflector 2. Rising from the reflector are posts 3 which support a platform 4 consisting of a flat annular metal plate having holes through which said posts pass. The posts are preferably screwthreaded for nuts 5 75 on which the platform rests and by means of which it can be adjusted up or down. Receptacles 6 are secured in apertures in said platform with their sockets opening downward, so that the lamps 7 must be inserted into said sockets from below, being thrust up through openings 8 in the reflector 2. These openings are notched at 9, or are otherwise irregularly shaped to afford air-passages through the reflector adjacent 80 to the lamp bulbs.

The cable 10 conveying current to the lamps passes down through a tube 11 screwed into a member 12, attached to the upper end of the stem 1. A hook 13 is secured to the upper end of the tube and has a longitudinal hole in line with said tube 100 for the passage of the cable.

A spun metal casing incloses the stem, 105 platform and tube. It is preferably made in three parts; a canopy 14, a bell 15 having a flat top with a central hole fitting the tube 11 so that said bell is supported by the member 12, and a body 16 somewhat smaller in 110 diameter at its top than the mouth of the

bell, into which it is telescoped and to which it is rigidly connected by studs 17, leaving a narrow annular passage between the bell and the body.

5. Jointed to the lower end of the stem is a rod 18, which carries at its lower end a flaring holder 19 by means of which the diffusing translucent globe 20 is supported. The globe has a central aperture in its bottom, and the holder has perforations 21 to admit air to the globe. The rim of the globe is held firmly up against the reflector 2, within an inclosing flange 22 on said reflector.

10. 15. A wide diffusing reflector 23 may be secured to the edge of the inner reflector 2, if desired. This style is especially suited for stores and mills, where large areas are to be illuminated.

20. 25. By raising or lowering the platform, lamps of different sizes can be employed, their bulbs being adjusted to the proper position to effect the best distribution of light. Air entering at the perforations 21 rises past the bulbs and flows through the openings in the reflector, the central opening of the platform and around its edges, and finally out by the annular passage between the body and the bell, carrying off the heat and keeping the cluster cool.

30. In accordance with the provisions of the patent statutes, I have described the principle of operation of my invention, together with the apparatus which I now consider 35 to represent the best embodiment thereof; but I desire to have it understood that the apparatus shown is only illustrative, and that the invention can be carried out by other means.

40. 45. What I claim as new and desire to secure by Letters Patent of the United States is:

1. A diffusing cluster comprising a horizontal reflector having openings, a platform supported above said reflector and vertically adjustable with reference to said reflector,

and incandescent lamps suspended from said platform and passing through said openings.

2. A diffusing cluster comprising a reflector having openings, posts rising from said reflector, a platform adjustably supported on said posts, and lamp sockets mounted on said platform in line with the openings in said reflector.

3. A diffusing cluster, comprising a reflector having openings, a platform adjustably supported above said reflector, downwardly opening lamp sockets mounted on said platform in line with said openings, and a diffusing globe supported below said reflector.

4. The combination with a reflector, of a diffusing globe below the same, incandescent lamps inclosed by said globe, and means for adjusting said lamps up or down with reference to said reflector.

5. The combination with a reflector having openings of irregular shape, of incandescent lamps received in said openings, a diffusing globe inclosing said lamps and having an opening at its lower end, and a casing above said reflector provided with vents.

6. In a diffusing cluster, the combination with a stem, of a reflector centrally supported thereby and provided with openings, an annular platform above said reflector, means for vertically adjusting said platform, lamp sockets mounted on said platform in line with the openings in said reflector, a rod jointed to said stem, a diffusing globe supported by said rod below said reflector, and a sheet-metal casing surrounding said platform and stem.

In witness whereof, I have hereunto set my hand this 28th day of August 1909.

WALTER D'A. RYAN.
